Attorney

UNITED STATES PATENT OFFICE.

HENRY C. MOHR, OF VICTOR, IOWA.

FENCEPOST.

Application filed April 13, 1923. Serial No. 631,949.

To all whom it may concern:

Be it known that I, HENRY C. MOHR, a citizen of the United States of America, and a resident of Victor, Iowa County, Iowa, 5 have invented certain new and useful Improvements in Fenceposts, of which the following is a specification.

My invention relates to improvements in fence posts, and one object of my improvements is to supply a metal post having 10 engaging-means for fence wires therealong, and also means thereon for securing fence boards thereto.

Another object is to provide an efficient 15 anchor-body mounted upon the lower part of the post to secure it in the ground more firmly.

Another object is to furnish a removable 20 cap-body for the post, having parts for engaging the upper end of the post, for use as a driving-head in the driving of the post into the ground.

These objects I have accomplished by the 25 means which are hereinafter described and claimed, and which are illustrated in the accompanying drawings, in which Fig. 1 is an elevation of my improved fence post; Fig. 2 is an elevation thereof taken at an angle of ninety degrees to the elevation of 30 said Fig. 1, and Fig. 3 is an elevation of the side of the post opposite that shown in said Fig. 2. Fig. 3 is a perspective view of the driving-head as detached, and Fig. 5 is a horizontal cross section of the post taken 35 on the dotted line 5—5 of said Fig. 2.

For the purpose of utmost strength and symmetry in the steel or iron post 1, I 40 preferably use an X-bar with its four equidistant longitudinal ribs. At the lower end of the post the ribs are obliquely cut away to provide a pointed terminal 2 which may easily penetrate the ground.

In order to removably secure a plurality 45 of horizontal fence-wires 5 to the post, I provide vertically ranged orifices 3 along one rib thereof with an upwardly inclined cut or slot 4 leading from each orifice 3 to the edge of said rib. As shown in Fig. 2 near its top this slot permits a narrow 50 tongue to be bent inclinedly to one side, leaving an opening through which a fence-

wire 5 may be passed to enter the orifice 3, and then the tongue is bent back to prevent escape of the wire, but in case it is desired to remove the wire, the tongue may be again 55 bent outwardly and the wire taken out.

As it sometimes becomes necessary to secure fence boards also to the post, wooden slabs 6 are positioned along opposite faces of another rib of the post longitudinally 60 and secured removably to the rib by means of bolts 7 passed through alined apertures in the slabs and rib and secured by means of nuts 8. Fence or other boards may then be nailed or otherwise fastened upon the 65 slabs 6.

Immediately above the point 2 of the post 1 an anchor is fastened upon the post. This may be made of two like but reversed plates 11 riveted at 12 to faces on the same side of 70 opposite ribs. The anchor as a whole is triangular with its apex positioned downwardly to aid it in penetrating the ground when the post is driven. The side angles of the anchor at 9 may be crimped from above 75 downwardly and divergently at 10. This anchor when embedded in the ground strongly resists upward or lateral displacements of the post, by reason of its wider surface and the sloping crimps. 80

The numeral 12 denotes a discoidal plate or cap-body having depending projections 13, preferably in pairs spaced apart, the projections being then removably fitted upon the top of the post 1 astride the ribs 85 thereof, and serves as a driving-head to receive blows in the driving of the post, without injury to the post.

Having described my invention, what I claim as new, and desire to secure by Letters 90 Patent, is:

A ribbed metal post having its lower end pointed, and downwardly diminished anchor-plates fastened on certain of the ribs of the post immediately above the 95 pointed end thereof, each plate having a crimp providing a relatively wide downwardly and outwardly inclined trough.

Signed at Victor, Iowa, this 10th day of March, 1923.

HENRY C. MOHR.
